THREAD HOLDER

Isidore Handzelek, Elizabeth, N. J.

Application May 23, 1940, Serial No. 336,763

8 Claims. (Cl. 242—134)

This invention relates to thread holders and has for an object to provide an improved construction which is adapted to be mounted to rotate in a fixed position or to be mounted on a trolley to be moved from place to place and present at all times a plurality of threads ready to be used.

Another object of the invention is to provide a thread holder having a body in which a number of spools of thread are mounted and means associated with the body for providing a proper tension for the respective threads as they are fed from the spools.

A further object of the invention is to provide a thread holder wherein different color threads are provided and wherein fabric members are presented for each color thread to indicate the color of thread associated therewith.

An additional object of the invention is to provide a thread holder having a body for supporting or carrying a plurality of threads and means for providing a tension to each thread while presenting, in addition, a cutting structure for the respective threads.

25 In the accompanying drawings—

Fig. 1 is a perspective view of a thread holder disclosing an embodiment of the invention, the same being shown mounted on a trolley;

30 Fig. 2 is an enlarged central vertical view through the holder disclosed in Fig. 1;

Fig. 3 is a horizontal sectional view through Fig. 2 approximately on the line 3—3;

Fig. 4 is an enlarged detail fragmentary sectional view through Fig. 1 approximately on the 35 line 4—4;

Fig. 5 is a transverse sectional view through Fig. 4 on the line 5—5.

Referring to the accompanying drawings by numerals, 1 indicates the body of the thread holder embodying certain features of the invention, and 2 a cover for said body. The body 1 is provided with a bottom 3 to which a depending standard 4 is connected and also to which a suspending or supporting bar 5 is connected. The 45 supporting bar 5, at the lower end, is provided with a pair of feet 6 and the upper end of the bar or standard 4 is provided with feet 7. Retaining bolts 8 and 9 extend through the respective feet and through the bottom 3, whereby all 50 parts are rigidly secured together. In addition, there is provided an annular member or wall 10 having inwardly extending ears 11 through which the respective bolts 8 and 9 project, whereby this member is also held in place by the same fastening means. Bar 5, adjacent the upper end, is

provided with a notch 12 which is adapted to engage a portion of the bottom 13 of cover 2, so as to support the same above the body 1. An aperture 14 is provided at the upper end of the bar 5 and a hook 15 is snapped through this aperture. 5 A ring 16, as shown in Fig. 1, is swiveled on the end of hook 15 so that the ring 16 may be supported by a nail, wire or other device, or by a strap 17 as shown in Fig. 1. This strap has a hook 18 at the lower end extending through the 10 ring 16 and a hook-shaped upper end 19 carrying a pulley 20, which pulley rides on the trolley wire 21, which wire may be supported in any desired manner.

By reason of the construction above described 15 and as shown in Fig. 1, the device may be moved along and come to rest at any point on the wire 21, so as to be in a convenient place for use. The device is intended for use primarily in tailoring 20 shops though it could be used in other places without departing from the spirit of the invention. Where a number of tailors are working it is preferable to have one of the devices for each tailor, but where one person is running a tailoring shop the trolley wire 21 and associated parts are 25 desirable as the device may be readily shifted from place to place by merely pushing or pulling the same. The body 1 is provided with the bottom 3, as shown in Fig. 2, an annular upstanding wall 22 and a plurality of ears 23. The wall 22 is 30 preferably arranged at the periphery of the bottom 3 and may be integral with the bottom or rigidly secured thereto by soldering or in any other desired way. Preferably all the parts here- 35 tofore described are made of metal though they could be made of other material without departing from the spirit of the invention.

A plurality of pins 24 are carried by the bottom 3 and on each of these pins there is provided a spool 25 carrying thread 26. The wall 22 40 is provided with a pressed-out ear 27 adjacent each of the pins 24, whereby there will be provided an opening 28 adjacent each ear and adjacent each spool 25. In the accompanying drawings eight pins 24 have been shown, as illustrated 45 in Fig. 3, but it will be understood that more or less could be used without departing from the invention. If there are eight pins 24 there will be eight openings 28 and associated parts. On each ear 27 there is mounted a manually adjustable thread-tension device 29 and when the holder is in use the threads from the respective spools extend through the respective tension devices. In addition, the respective threads extend through 50 apertures 30 in the respective ears 23 and through 55

the respective fabric members 31 secured to the respective ears 23 by the bolts 32. The fabric members 31 are intended to be of the same color or shade as the thread 26 on the spool 25 adjacent the same. By reason of this fact, the workman may readily observe the fabric members 31 and if the shade is the kind desired he will merely pull the thread end 33 to secure the desired length of thread and will know that the same will be of the right color. The thread ends 33 extend through the respective fabric members 31, which prevents any accidental movement of the threads but permits movement when the threads are pulled. In addition the fabric members 31 hold the ends 33 spaced apart ready to be grasped by the workman.

As shown particularly in Figs. 1 and 2, the standard 4 is secured to a cross bar 34 by the respective bolts 35 and 36 which extend through ears 37 and 38 formed from the end of the standard 4. In addition, bolts 35 and 36 extend through the double-edged knife or cutter 39 and through a base plate having a plurality of spaced fingers 41 on each edge. These fingers overlap the respective cutting edges of the knife 39 and function as a guard to prevent injury to the hand of a workman and has means to guide a thread against the cutting edge when it is desired to sever the same. At the extreme outer end of the bar 34 there are provided pins 42, each having a threaded extension 43 adapted to receive the respective nuts 44 and 45. A washer 46 is also provided. The nut 44 acts as a stop or abutment while the nut 45 clamps the parts in place as shown in the accompanying drawings. Several layers of fabric 46 are clamped in place and function as needle holders. As the workman uses a number of different needles he may stick them into the fabric 46 when not desired and they will be in position to be grasped at any time. The pins are adapted also to receive thimbles 47 so that they also will be ready for use at any time.

Referring to the annular wall 10, it will be noted that this wall, together with the bottom 3, forms a chamber in which different articles may be placed. The cover 2 is provided with an annular depending portion 2', as shown in Fig. 2, so as to telescope a short distance over the upper open end of the wall 22 and provide a chamber 48 for the reception of desired articles, as for instance, odd color threads, scissors and the like. Also from Fig. 2 it will be noted that the bar 5 is provided with an aperture 49 which is adapted to receive a padlock 50, if desired. Where a number of devices are used in a shop employing a number of workmen, it may be desirable to use a padlock 50 so that none of the spools 25 may be removed without proper authority. When it is desired to move the cover 2 in order to secure access to the spools 25 or to the articles in the container formed by the wall 10 and the bottom 3, the cover 2 is raised and held supported as illustrated in dotted lines in Fig. 2.

65 I claim:

1. A thread holder comprising an enclosure, a plurality of spool-carrying pins arranged in said enclosure, said enclosure having an opening in the side thereof adjacent each of said pins, a thread tension device carried by said enclosure adjacent each of said openings, and a piece of fabric carried by said enclosure immediately below each of said tension devices.

2. A thread holder including a support, a plurality of thread carriers mounted on said holder, a thread tension device carried by said holder for each of the thread carriers, and fabric means adjacent each of said tension devices for holding the thread ends from said tension devices against other than a positive pull. 5

3. A thread holder as set forth in claim 2, characterized by forming said fabric means out of fabric of the same color as the thread with 10 which they are associated.

4. A thread holder including a body having a bottom and an annular wall upstanding from said bottom, said wall having a plurality of ears pressed therefrom and positioned to extend radially with an opening in the wall adjacent each ear, a spool carrier mounted on said bottom adjacent each of said openings, and a thread tension device mounted on each of said ears, thread from the respective spools mounted on said carriers being adapted to extend through the tension devices when the thread holder is in use. 15 20

5. A thread holder including a plurality of spaced supporting carriers, means for supporting said carriers, and a fabric member carried by said means for each of said carriers, threads from the spools on said carriers being adapted to extend respectively through said fabric members, said fabric members being of substantially the color as the thread extending therethrough. 25 30

6. A thread holder including a body formed with a bottom and an annular upstanding wall having openings therein, a spool carrier mounted on said bottom adjacent each of said openings whereby threads from said spools may extend through the openings, and a fabric member carried by said body for each of said openings, the thread extending through the respective openings being adapted also to extend through said fabric member for preventing movement of the 40 thread except when pulled. 35

7. A thread holder including a body formed with a round bottom and an upstanding annular wall at the periphery of said bottom, said wall having at spaced points ears pressed therefrom whereby there is presented an opening adjacent each ear, a spool-supporting pin carried by said bottom adjacent each of said openings, a thread tension device mounted on each of said ears through which thread from the respective spools are adapted to extend when the holder is in use, said bottom being provided with an extending ear adjacent each of said openings, a fabric member for each of the ears extending from said bottom, means for firmly clamping the respective fabric members to the respective ears, and means connected with said bottom for rotatably supporting said body. 45 50 55

8. A thread holder as set forth in claim 7, characterized by a cover telescopically fitting over the upper edge of said annular wall, said cover having a bottom member having a rectangular slot positioned centrally, said rotatable supporting means including a supporting bar rectangular in cross section and slidably extending 60 65 through said cover, said supporting bar adjacent the end farthest from said body being provided with a notch in which part of the bottom of the cover is adapted to fit when the cover is suspended above said body.
